ABSTRACT OF THE DISCLOSURE

Device for pulling a leading end of yarn from a coil includes coil holder means for rotating a yarn coil about its axis, a suction nozzle having a suction mouth adjacent the holder means to induct an air current for pulling the yarn end off the rotating coil, mechanical clamping means located in the suction-air current of said nozzle, and means for moving the clamping means periodically into engagement with the yarn end within the suction-air current for supplementing the entraining action of the suction-air current to grip the yarn end intermittently.

Specification

Our invention relates to a device for pulling the leading yarn end from a rotating spinning cop, cheese or other coil by means of a suction nozzle whose mouth is located close to the coil peripheral surface.

It is known to seek the yarn on a spinning cop or a cheese, cone or other yarn package by placing the mouth of a suction nozzle at a slight distance from the rotating body of yarn, so that the starting length of yarn is sucked into the nozzle and then pulled off the yarn body or held arrested in the nozzle by the pulling force of the suction air current.

It has been found that under particular operating conditions, the yarn may form a number of turns or a bunch which is wound in the direction opposed to the winding sense of the yarn body. Such a "counter winding" may come about, for example, if the yarn to be pulled off is clamped between individual yarn layers of the coil and is entrained by these yarn layers during rotation of the coil. This occurs particularly in cases where the suction force of the nozzle is weak or becomes weak due to a relatively slight negative pressure or because the spacing between nozzle mouth and yarn body is too large. The latter event is apt to occur, for example, with spinning cops when the nozzle is to act not only upon the cylindrical but also upon the conical portion of the yarn body.

It is virtually impossible to adapt the shape of the nozzle mouth to that of the conical portion near the tip of a cop, because the position and shape of the conical portion vary greatly even if one and the same output of a spinning machine is being wound upon a multiplicity of spinning cops. For that reason, there exists a relatively large spacing between the suction nozzle and the starting cone of such cops, so that at the starting cone the pulling force of the current of suction air is lower than at the cylindrical, major portion of the yarn body constituted by the cop, with the result that in the vicinity of the conical portion, there may be insufficient resistance to the formation of counter windings.

It is accordingly an object of the invention to prevent the occurrence of opposingly wound yarn turns or bunches on the body of yarn from which the leading end is being pulled off by suction.

It is a more specific object of our invention to reliably prevent the possibility of counter-winding formation even if the operating conditions are such as to normally pre-

2

sent the danger of such formation because of a relatively large spacing between nozzle mouth and coil or because of any other circumstances apt to reduce the suction force of the nozzle at a particular locality of the coil.

To this end, and in accordance with our invention, we provide the device for suctionally pulling the leading end of yarn from a coil with gripper means for periodically seizing the yarn end located in the suction flow path of the suction nozzle whose mouth is adjacent the holder means which accommodates the coil of yarn and rotates it about its axis when the suction nozzle acts to pull the leading end of yarn from the coil. The gripper means are of such construction that when the yarn end is periodically seized or clamped thereby and as the coil continues rotating, any catches formed in the yarn, which cause the aforementioned counter windings, are accordingly torn away. The loosened yarn loop, present when the gripper means are released, is then entrained by the suction flow and sucked away.

According to other features of our invention, the gripper means comprise a pair of oscillatable, periodically overlapping yarn-diverting members located in front of the mouth of the suction nozzle. The members are formed of channels having a U-shaped profile, the legs thereof extending toward one another so as to intermesh, and by supplementing the entraining or clamping of the yarn produced thereby, resistance is effected against the withdrawal of the yarn from the nozzle when a counter-winding is formed. Since the yarn can then no longer be withdrawn from the nozzle without very great resistance, the yarn catch which can cause the formation of a counter-winding, is torn away as the coil continues to rotate. The loosened loop then present can be rapidly sucked away as in the aforementioned case when the meshing yarn-diverting members are separated from one another.

Other features which are considered as characteristic for the invention are set forth in the appended claims.

Although the invention is illustrated and described herein as embodied in device for pulling the lead end of yarn from a textile coil, it is nevertheless not intended to be limited to the details shown, since various modifications and structural changes may be made therein without departing from the spirit of the invention and within the scope and range of equivalents of the claims.

The construction and method of operation of the invention, however, together with additional objects and advantages thereof will be best understood from the following description of a specific embodiment when read in connection with the accompanying drawing, in which:

FIG. 1 is, by way of example, a schematic plan view of an embodiment of a yarn-end pulling device constructed in accordance with our invention; and

FIG. 2 is a section taken along the line II—II of FIG. 1 in the direction of the arrows.

Referring now to the drawing, there is schematically shown a spinning cop 1 accommodated between two guiding abutments 2 and 3 which have respective funnel-shaped recesses for centering and clamping the cop 1 in coaxial alignment with the respective shafts of the holders 2 and 3. The holder 3 is shown driven from a suitable drive 14. A suction nozzle 4 has a mouth opening located at 4b at a small distance from the peripheral surface of the cop 1, the length of the mouth opening being substantially equal to the axial length of the yarn body of the cop. The starting length of yarn is to be pulled off the cop 1 by the suction produced by the nozzle 4. It will be recognized that due to the varying distance between the nozzle mouth and the peripheral surface of the coil, the suction force varies accordingly along the length of the cop. That is, in the vicinity where the yarn body is conical, namely at C in the vicinity of the coil tip, the suction force is lower than at the cylindrical portion B. Conse-

quently, the danger of counter-winding formation is largest in the conical region C.

As shown in the sectional view of FIG. 2, a sheet-metal channel 6 of U-shaped profile is located substantially along the starting cone C of the spinning cop 1 at the mouth 4b of the suction nozzle 4. A rocker arm 8 is mounted on the nozzle 4 and is pivotable intermediate its ends about a pin 7. At the lower end of the rocker arm 8, as seen in FIG. 2, another sheet-metal channel 6' of U-shaped cross section is secured as by soldering, welding or any other suitable fastening means. One end of a coupling 9 is secured as by a pivot pin to the other end of the rocker arm 8, and the free end of the coupling 9 is fastened to a cam disc 10 which is rotated by a motor 5 through suitable transmission means that are not illustrated. The rocker arm 8 thus rocks back and forth so that the edges of the U-shaped channel 6' periodically overlap the edges of the U-shaped channel 6. The yarn end sucked into the nozzle 4 is consequently seized and drawn into the channels 6 and 6'. Due to the additional clamping of the yarn produced thereby, resistance is applied against the withdrawal of the yarn from the nozzle when a counter-winding is formed. Since the yarn can then no longer be withdrawn from the nozzle without very great effort, the yarn catch, which can cause the formation of a counter-winding, is torn away as the coil continues rotating. When the rocker arm 8 disengages the U-shaped channels 6 and 6', the loosened loop then present is rapidly sucked away before the yarn is again clamped by the periodically overlapping yarn-diverting members. It has also been found to be advantageous to provide a drive for the rocker arm 8 which will produce oscillations thereof at a frequency having a magnitude in the tens of the number of revolutions of the cop.

We claim:

1. Device for pulling a leading end of yarn from a coil, comprising coil holder means for rotating a yarn coil about its axis, a suction nozzle having a suction mouth adjacent said holder means to induct an air current for pulling the yarn end off the rotating coil, mechanical clamping means located in the suction-air current of said nozzle, and means for moving said clamping means periodically into engagement with the yarn end within the suction-air current for supplementing the entraining action of the suction-air current to grip the yarn end intermittently.

2. Device according to claim 1, wherein said clamping means comprises a pair of yarn-diverting members mounted for oscillation relative to one another on said suction nozzle, said yarn-diverting members having edges that are periodically mutually overlapping.

3. Device according to claim 2, wherein said yarn-diverting members are located at the mouth of said suction nozzle.

4. Device according to claim 2, wherein said yarn-diverting members are in the form of a channel having a substantially U-shaped cross section.

5. Device according to claim 4, wherein one of said channels is fixed to an edge of said suction mouth and the other of said channels is carried by a rocker arm and oscillatable into periodic overlapping relationship with said fixed channel.
